CLAIM

The ornamental design for a golf club head holder belt, as shown and described.

DESCRIPTION

FIG. 1 is a front elevational view of a golf club head holder belt showing my new design, with the cross-hatching shown to indicate surface character—the broken line lettering on the pockets being for illustrative purposes only and forming no part of the claimed design;

FIG. 2 is a top plan thereof;

FIG. 3 is a bottom plan view thereof;

FIG. 4 is a left side elevational view thereof;

FIG. 5 is a right side elevational view thereof; and,

FIG. 6 is a rear elevational view thereof.

The belt shown broken away in FIGS. 1-3 and 6 to indicate indeterminate length.
